LOCOMOTIVE TENDER

Nathan M. Lower, Erie, Pa., assignor to The Standard Stoker Company, Incorporated, a corporation of Delaware

Application December 16, 1937, Serial No. 180,095

13 Claims. (Cl. 105—234)

This invention relates to locomotive tenders which are equipped with a fuel conveyor of a locomotive stoker.

It is an object of this invention to improve the 5 drive mechanism associated with the rearward end of the fuel conveyor.

Specifically, it is an object of this invention to provide a novel arrangement in a drive mechanism for the tender conveyor of a locomotive 10 stoker whereby inspection and repair of such drive mechanism is facilitated.

A further object of this invention contemplates an arrangement in a locomotive tender whereby access to the interior of the drive gearing for the 15 stoker conveyor may be had from the fuel bin.

Other objects, together with their attendant advantages will become apparent as the following description is read in connection with the accompanying drawings, in which

20 Fig. 1 is a vertical medial section through the forward portion of a locomotive tender with the invention as viewed along the line 1—1 of Fig. 2;

Fig. 2 is a transverse sectional view taken on the line 2—2 of Fig. 4;

25 Fig. 3 is a fragmentary sectional view taken on the line 3—3 of Fig. 2;

Fig. 4 is an enlarged fragmentary sectional view of Fig. 1;

Fig. 5 is a view similar to Fig. 4 illustrating a 30 modification, as viewed along line 5—5 of Fig. 6;

Fig. 6 is a transverse sectional view taken along the line 6—6 of Fig. 5; and

Fig. 7 is a sectional view taken on the line 7—7 of Fig. 6.

35 Referring to Figs. 1 to 4, inclusive, the tender T includes a base frame 10 upon which is supported a tank 11 having a fuel compartment 12 and a water compartment 13. The fuel compartment 12 is separated from the water compartment 13 by the rear slope sheet 14, side slope sheets 15, 16 and the bottom sheet 17. Between the lower ends of the slope sheets 14, 15 and 16, the bottom sheet 17 is provided with a central slot or aperture 18 through which coal is adapted to fall 40 into a trough conduit 19 of the stoker conveyor C. A series of slidable plates 20 are utilized for controlling the effective size of the aperture 18 whereby coal may be fed into the trough conduit 19 from successive zones within the fuel compartment 12.

50 In transverse cross section, the trough conduit 19 is approximately V-shaped with vertical sides 21, 22 terminating slightly below the bottom sheet 17. Along each respective vertical side 21, 22, the trough conduit 19 is provided with an outwardly turned angle iron 23, 24 whereby the trough conduit 19 may be firmly secured to the underside of the bottom sheet 17 in water-tight fashion.

55 At its forward end, the trough conduit 19 is

provided with an imperforate plate 25 having a foot 26 secured to the base frame 10. Intermediate foot members 27 are also utilized for supporting the trough conduit 19 above the frame 10. A conveyor screw 28 is rotatably mounted in 5 the trough conduit 19 and urges fuel forwardly. Oversize lumps of fuel are engaged by teeth of a crusher 29, which is secured to the plate 25, and reduced to proper size. On the forward side of the plate 25 a spherical shell 30 is secured by 10 bolts 31 to form one element of a ball and socket connection between the conveyor C and a conveyor leading forwardly to the locomotive (not shown).

The conveyor screw 28 is operated from its rear- 15 ward end of drive means D comprising a gear housing 32 provided on its front wall 33 with a flange 34 to which the rear end 35 of the trough conduit 19 is secured in a water-tight manner. The rear wall 36 of the gear housing 32 is imper- 20 forate and has secured thereto a plate 37, forming a support for the rearward end of the conveyor C. Considered in transverse cross section, the gear housing 32 is approximately U-shaped, opening upwardly through its top. The upper 25 portion of the gear housing 32 is bounded by a lateral flange 38 which is secured to the under side of the bottom sheet 17 so as to form a water tight joint. The opening 39 in the upper portion of the gear housing is closed by a detachable 30 cover 40 which is spaced below a hinged portion 41 of the bottom sheet 17.

At one side of the trough conduit 19 is a tube 42 (Figs. 2 and 3) within which is mounted a 35 drive shaft 43 leading from a suitable prime mover. The tube 42 extends between the plate 25 and the front wall 33 of the gear housing 32, being secured thereto by means of welding as indicated in Fig. 3. A coupling member 44 is carried by the shaft 43 and it is adapted to operatively engage 40 the forward end 45 of the primary pinion shaft 46 by means of a bolt 9. In axial alignment with the shaft 43, the gear housing front wall 33 is provided with a bore 47 within which a bearing 48 is received. Longitudinal movement of said 45 bearing 48 with respect to said bore 47 is restrained by a set screw 50 which engages a groove 49 extending circumferentially of said bearing 48. The front journal 51 of the primary pinion shaft 46 is mounted in the bearing 48 while the 50 rear journal 52 of this shaft is mounted in a bearing 53 formed in the imperforate rear wall 36 of the gear housing 32. Intermediate the journals 51, 52, the shaft 46 is provided with a pinion 54 which is cut on the shaft and being of a 55 diameter less than the diameter of the bore 47.

The pinion 54 is meshed by a gear 55 mounted upon an intermediate shaft 56. The rear journal 57 of the shaft 56 is mounted in a bearing 58 formed in the imperforate rear wall 36, while the 60

front journal 59 of the shaft 56 is mounted in a bearing member 60 which is detachably secured to the front wall 33 of the gear housing 32 within the confines of the trough conduit 19. Adjacent 5 its rear journal 57, the intermediate shaft 56 carries a key or feather 61. This key 61 enters a key way in the hub of the intermediate gear 55, providing a driving connection between the shaft 56 and the gear 55 while permitting removal of the 10 shaft 56 and key 61 in a forward direction. Immediately rear of the front journal 59, the shaft 56 has cut thereon an intermediate pinion 62, the external diameter of which is less than the bore 63 of the front wall 33 and into which bore 15 33 the bearing member 60 is fitted.

The intermediate pinion 62 meshes with a gear 64 mounted on the main drive shaft 65 arranged axially of the conveyor screw 28. Rearward of the gear 64, the shaft 65 is provided with a rear journal 66 mounted in a bearing 67 formed in the imperforate rear wall 36. The front journal 68 of shaft 65 is mounted in a bearing 69 formed in the front wall 33, the internal diameter of said bearing 69 being large 25 enough to permit forward withdrawal of the shaft 65 and key 70 which is utilized to operatively connect the gear 64 to the shaft 65. A polygonal forward portion 71 of the shaft 65 enters a corresponding socket 72 in the conveyor screw 28, forming a driving connection between the conveyor screw 28 and the main drive shaft 65. A plate 73 is secured to the forward side of bearing 69 and prevents forward motion of the main drive shaft 65 during normal stoker operation. Thrust washers 74, 75 are disposed between the plate 73 and the rear of conveyor screw 28. To prevent the conveyor screw 28 and drive shaft 65 from pulling apart during normal stoker operation, a bolt 76 is used.

40 Whenever it is desired to inspect the condition of the gears within the housing 32, it may be done from within the fuel compartment 12 by swinging open the hinged portion 41 of the bottom sheet 17. This exposes the cover 40, 45 which may then be detached and an inspection made through the opening 39. The gears and associated shafting may also be removed by a mechanic while in the fuel compartment 12. With the slidable plates 20 moved forwardly 50 to form an opening immediately above the rear portion of the trough conduit 19, the intermediate pinion shaft 56 may be withdrawn forwardly upon removal of the detachable bearing member 60. It will be understood that the 55 hinged portion 41 of the bottom sheet 17 is first removed and the cover 40 detached, so that as the pinion shaft 56 is drawn forwardly, the gear 55 may be removed through the opening 39. In order to remove the gear 64 and the 60 main drive shaft 65, the conveyor screw 28 is uncoupled and plate 73 removed to permit forward withdrawal of the main drive shaft 65. The gear 64 is removed through the opening 39. By loosening the set screw 58, the drive 65 shaft 43, bearing 48 and primary pinion shaft 46 may be withdrawn through the tube 42.

In the modification shown in Figs. 5 to 7, inclusive, the trough conduit 75 is supported above the tender base frame 10 and carries a 70 gear housing 76. The trough conduit 75 and gear housing 76 are each provided with a flange 77 to which is attached the lower ends of the fuel bin forming slope sheets 14, 15 and 16. The upper side of the gear housing 76 is provided 75 with an opening 78 which is covered by a de-

tachable cover 79 disposed within the fuel compartment 12.

A conveyor screw 28 is rotatably mounted in the trough conduit 75 and it is operatively connected to the drive shaft 80 which is journaled in the gear housing 76 and has keyed thereto a drive gear 81. The front journal 82 of the shaft 80 is carried by a bearing member 83 detachable from the front wall 84 of the gear housing. At one side of the trough conduit 75 a bearing 85 is formed, to the forward side of which a tube 86 is secured for housing the shaft 87. The shaft 87 is journaled in the bearing 85 and enters into a cavity 88 within which it is coupled at 89 to the pinion shaft 90. A detachable bearing 91 supports the pinion shaft 90 which is provided with a pinion 92 meshing with the gear 81. The cavity 88 opens laterally into the trough conduit 75. If desired, a detachable guard plate 93 may be used to cover the opening between the trough conduit 75 and the cavity 88.

As in the preferred form, inspection of the gearing may be had from a position in the fuel compartment 12 by removing the cover 79 over the opening 78. With the cover 79 removed and the slidable plates 94 moved forwardly to establish communication between the fuel compartment 12 and the trough conduit 75, the gears and associated shafts may be removed substantially as described in connection with the preferred form of the invention. To remove the pinion shaft 90, the shaft 87 is withdrawn through tube 86, then the guard plate 93 is removed to permit removal of coupling 89 and bearing 91, whereupon the pinion shaft 90 may be withdrawn into the cavity 88. In like manner, the conveyor screw 28 is uncoupled and bearing member 83 detached to permit forward withdrawal of shaft 80. The drive gear 81 may be removed through the opening 78.

It will thus be seen that by the present invention, inspection and repair of locomotive stoker drive mechanism can be readily accomplished.

I claim:

1. In a locomotive tender having a floor and a fuel compartment above said floor, a stoker conveyor positioned below the level of said floor, said stoker conveyor including a trough conduit and a conveyor screw rotatably mounted in said trough conduit, and drive mechanism for operating said conveyor screw from its rearward end, said drive mechanism including a gear housing provided with an upward opening directed within the confines of said fuel compartment, said gear housing including a rear wall and a front wall forming a closure for the rear portion of said trough conduit, a drive shaft in said gear housing operatively connected to said conveyor screw, a bearing at the front wall of said gear housing for supporting said drive shaft, a gear in said housing operatively connected to said drive shaft, said drive shaft arranged to be withdrawn from said gear housing through the front wall thereof and said gear arranged for withdrawal through the upward opening of said gear housing upon withdrawal of said shaft through the front wall of the gear housing, and a detachable cover for said upward opening, said cover being accessible from said fuel compartment. 70

2. In a locomotive tender having a floor and a fuel compartment above said floor, a stoker conveyor positioned below the level of said floor, said stoker conveyor including a trough conduit and a conveyor screw rotatably mounted in said 75

trough conduit, and drive mechanism for operating said conveyor screw from its rearward end, said drive mechanism including a gear housing provided with an upward opening directed within the confines of said fuel compartment, said gear housing including a rear wall and a front wall forming a closure for the rear portion of said trough conduit, a drive shaft in said gear housing operatively connected to said conveyor screw, a bearing detachably secured to the front wall of said gear housing for supporting said drive shaft, a gear in said housing operatively connected to said drive shaft, said drive shaft arranged to be withdrawn from said gear housing through the front wall thereof and said gear arranged for withdrawal through the upward opening of said gear housing upon withdrawal of said shaft through the front wall of the gear housing, and a detachable cover for said upward opening, said cover being accessible from said fuel compartment.

3. In a locomotive tender having a floor and a fuel compartment above said floor, a stoker conveyor positioned below the level of said floor, said stoker conveyor including a trough conduit and a conveyor screw rotatably mounted in said trough conduit, and drive mechanism for operating said conveyor screw from its rearward end, said drive mechanism including a gear housing provided with an upward opening directed within the confines of said fuel compartment, said gear housing including a rear wall and a front wall forming a closure for the rear portion of said trough conduit, a pair of shafts in said gear housing, bearings at the front wall of said gear housing for supporting said shafts, a gear mounted on each of said shafts, each of said shafts arranged to be withdrawn forwardly through the front wall thereof and said gears arranged for withdrawal through the upward opening of said gear housing upon withdrawal of said shafts through the front wall of the gear housing, and a detachable cover for said upward opening, said cover being accessible from said fuel compartment.

4. In a locomotive tender having a floor and a fuel compartment above said floor, a stoker conveyor positioned below the level of said floor, said stoker conveyor including a trough conduit and a conveyor screw rotatably mounted in said trough conduit, and drive mechanism for operating said conveyor screw from its rearward end, said drive mechanism including a gear housing provided with an upward opening directed within the confines of said fuel compartment, said gear housing including a rear wall and a front wall forming a closure for the rear portion of said trough conduit, a pair of shafts in said gear housing, detachable bearings at the front wall of said gear housing for supporting said shafts, a gear mounted on each of said shafts, each of said shafts arranged to be withdrawn forwardly through the front wall thereof and said gears arranged for withdrawal through the upward opening of said gear housing upon withdrawal of said shafts through the front wall of the gear housing, and a detachable cover for said upward opening, said cover being accessible from said fuel compartment.

5. In a locomotive tender having fuel and water compartments, partition plates separating said fuel and water compartments including a bottom sheet forming the floor of said fuel compartment, a stoker conveyor positioned below the level of said floor including a trough conduit

arranged to receive fuel from said fuel compartment, a conveyor screw rotatably mounted in said trough conduit, said trough conduit having a water-tight connection with said floor, and drive mechanism for operating said conveyor screw from its rearward end, said drive mechanism including a gear housing having a front wall and an imperforate rear wall, said gear housing provided with an upward opening directed within the confines of said fuel compartment, gearing and shafting disposed in said gear housing, said shafting arranged to be withdrawn forwardly through the front wall of said gear housing and said gearing arranged to be withdrawn through said upwardly directed opening upon withdrawal of said shafting through the front wall of the gear housing.

6. In a locomotive tender having fuel and water compartments, partition plates separating said fuel and water compartments including a bottom sheet forming the floor of said fuel compartment, a stoker conveyor positioned below the level of said floor including a trough conduit arranged to receive fuel from said fuel compartment, a conveyor screw rotatably mounted in said trough conduit, said trough conduit having a water-tight connection with said floor, drive mechanism for operating said conveyor screw from its rearward end, said drive mechanism including a gear housing having a front wall and an imperforate rear wall, said gear housing provided with an upward opening directed within the confines of said fuel compartment, gearing and shafting disposed in said gear housing, said shafting arranged to be withdrawn forwardly through the front wall of said gear housing and said gearing arranged to be withdrawn through said upwardly directed opening upon withdrawal of said shafting through the front wall of the gear housing, and a detachable cover for said upward opening, said cover being accessible from said fuel compartment.

7. In a locomotive tender having fuel and water compartments, partition plates separating said fuel and water compartments including a bottom sheet forming the floor of said fuel compartment, a stoker conveyor positioned below the level of said floor including a trough conduit arranged to receive fuel from said fuel compartment, a conveyor screw rotatably mounted in said trough conduit, said trough conduit having a water-tight connection with said floor, drive mechanism for operating said conveyor screw from its rearward end, said drive mechanism including a gear housing having a front wall and an imperforate rear wall, said gear housing provided with an upward opening directed within the confines of said fuel compartment, gearing and shafting disposed in said gear housing, said shafting arranged to be withdrawn forwardly through the front wall of said gear housing and said gearing arranged to be withdrawn through said upwardly directed opening upon withdrawal of said shafting through the front wall of the gear housing, and a detachable cover for said upward opening disposed below the floor of said compartment, said floor being provided with a detachable portion fitting over said cover.

8. In a locomotive tender having fuel and water compartments, partition plates separating said fuel and water compartments including a bottom sheet forming the floor of said fuel compartment, a stoker conveyor positioned below the level of said floor including a trough conduit arranged to receive fuel from said fuel compartment,

- ment, a conveyor screw rotatably mounted in said trough conduit, said trough conduit having a water-tight connection with said floor, drive mechanism for operating said conveyor screw from its rearward end, said drive mechanism including a gear housing having a front wall and an imperforate rear wall, said gear housing provided with an upward opening directed within the confines of said fuel compartment, gearing and shafting disposed in said gear housing, said shafting arranged to be withdrawn forwardly through the front wall of said gear housing and said gearing arranged to be withdrawn through said upwardly directed opening upon withdrawal of said shafting through the front wall of the gear housing, and a detachable cover for said upward opening disposed below the floor of said compartment, said floor being provided with a hinged portion fitting over said cover.
9. In a locomotive tender having fuel and water compartments, partition plates separating said fuel and water compartments including a bottom sheet forming the floor of said fuel compartment, a stoker conveyor positioned below the level of said floor including a trough conduit arranged to receive fuel from said fuel compartment, a conveyor screw rotatably mounted in said trough conduit, said trough conduit having a water-tight connection with said floor, and drive mechanism for operating said conveyor screw from its rearward end, said drive mechanism including a gear housing having a front wall and an imperforate rear wall, said gear housing being provided with an upward opening directed within the confines of said fuel compartment, gearing and shafting disposed in said gear housing, bearings detachably secured to the front wall of said housing for supporting said shafting, said shafting arranged to be withdrawn forwardly through the front wall of said gear housing and said gearing arranged to be withdrawn through said upwardly directed opening upon withdrawal of said shafting through the front wall of the gear housing.
10. In a locomotive tender having a floor and a fuel compartment above said floor, a stoker conveyor positioned below the level of said floor, said stoker conveyor including a trough conduit and a conveyor screw rotatably mounted in said trough conduit, and drive mechanism for operating said conveyor screw from its rearward end, said drive mechanism including a gear housing provided with an upward opening directed within the confines of said fuel compartment, said gear housing including a rear wall and a front wall forming a closure for the rear portion of said trough conduit, a drive shaft in said gear housing operatively connected to said conveyor screw, a gear in said housing operatively connected to said drive shaft, said drive shaft arranged to be withdrawn from said gear housing through one wall thereof and said gear arranged for withdrawal through the upward opening of said gear housing into said fuel compartment upon withdrawal of said drive shaft through the said one wall of the gear housing.
11. In a locomotive tender having a floor and a fuel compartment above said floor, a stoker conveyor positioned below the level of said floor, said stoker conveyor including a trough conduit and a conveyor screw rotatably mounted in said trough conduit, said trough conduit having a water-tight connection with said floor, drive mechanism for operating said conveyor screw from its rearward end, said drive mechanism including a gear housing having a front wall and an imperforate rear wall, said gear housing provided with an upward opening directed within the confines of said fuel compartment, said gear housing including a rear wall and a front wall forming a closure for the rear portion of said trough conduit, a drive shaft in said gear housing operatively connected to said conveyor screw, a gear in said housing operatively connected to said drive shaft, said drive shaft arranged to be withdrawn from said gear housing through one wall thereof and said gear arranged for withdrawal through the upward opening of said gear housing into said fuel compartment upon withdrawal of said drive shaft through the said one wall of the gear housing.
12. In a locomotive tender having a floor and a fuel compartment above said floor, a stoker conveyor positioned below the level of said floor, said stoker conveyor including a trough conduit and a conveyor screw rotatably mounted in said trough conduit, and drive mechanism for operating said conveyor screw from its rearward end, said drive mechanism including a gear housing provided with an upward opening directed within the confines of said fuel compartment, said gear housing including a rear wall and a front wall forming a closure for the rear portion of said trough conduit, a drive shaft in said gear housing operatively connected to said conveyor screw, a gear in said housing operatively connected to said drive shaft, said drive shaft arranged to be withdrawn from said gear housing through one wall thereof and said gear arranged for withdrawal through the upward opening of said gear housing into said fuel compartment upon withdrawal of said drive shaft through the said one wall of the gear housing.
13. In a locomotive tender having a floor and a fuel compartment above said floor, a stoker conveyor positioned below the level of said floor, said stoker conveyor including a trough conduit and a conveyor screw rotatably mounted in said trough conduit, and drive mechanism for operating said conveyor screw from its rearward end, said drive mechanism including a gear housing provided with an upward opening directed within the confines of said fuel compartment, said gear housing including a rear wall and a front wall forming a closure for the rear portion of said trough conduit, a drive shaft in said gear housing operatively connected to said conveyor screw, a gear in said housing operatively connected to said drive shaft, said drive shaft arranged to be withdrawn from said gear housing through the front wall thereof and said gear arranged for withdrawal through the upward opening of said gear housing into said fuel compartment upon withdrawal of said drive shaft through the front wall of the gear housing, and a detachable cover for said upward opening said cover being accessible from said fuel compartment.
